UNITED STATES PATENT OFFICE.

JACQUES D. DELILLE, OF PARIS, FRANCE.

MACHINE FOR MOLDING SAND.

SPECIFICATION forming part of Letters Patent No. 244,359, dated July 12, 1881.
Application filed March 18, 1881. (No model.) Patented in France March 31, 1880, in England April 8, 1880, and in Belgium June 18, 1880.

To all whom it may concern:

Be it known that I, JACQUES DÉSIRÉ DELILLE, of Paris, in the Republic of France, have invented a new and useful Improvement 5 in Machines for Molding Sand for Founders' Use and for other Purposes, of which improvement the following specification is a full description.

This invention relates to a molding-machine intended mainly for use in foundries and other 10 places where it is desired to obtain from patterns molds in sand suitable for casting metals; and it has for its object to enable molding operations to be carried on with regularity and 15 rapidity by ordinary workmen, and in a better and more economical manner than heretofore.

The principal parts of this machine are the rammer for compacting the sand in the flask, the sand-distributer for delivering the sand to 20 be compacted, and the table or support for the flask or molding-box. The rammer is reciprocated vertically, and is also made capable of lateral movement. The sand-distributer is a tube from which the sand is delivered around 25 the lower end of the rammer. This tube may have the head of the rammer attached at its lower end, and thus form a part of the rammer; or a separate tube surrounding the rammer can be employed. The table upon which the 30 flask is placed is lowered as the latter becomes filled with sand. Means are also employed for moving the flask laterally under the rammer, or for revolving it, as may be desired.

The following description will enable those 35 skilled in the art to which this invention relates to make and use the same, reference being had to the accompanying drawings, which form a part of this specification.

Figure 1 is an elevation of a machine constructed in accordance with the invention, and 40 with the sand-distributer formed by the upper part of the rammer. Fig. 1^a is a detail view in vertical section through the table for supporting the flask or molding-box; Fig. 2, a vertical section on line *ff'*, Fig. 1, illustrating the 45 devices for supplying the sand and for operating the rammer; Figs. 3 and 4, horizontal and vertical sections, respectively, showing the construction of the rammer at its lower end;

and Fig. 5, a bottom view of the head of the 50 rammer. The section represented in Fig. 3 is taken on the dotted line in Fig. 4. Fig. 6 is a horizontal section on line *f'f'*, Fig. 2; Fig. 7, a plan at the level of the table for the molding box or flask; Fig. 8, an elevation of a wheeled carriage that may be used for moving the molding box or flask under the rammer; Fig. 9, a vertical section illustrating a flexible rammer; and Fig. 10, an elevation of a machine, also constructed in accordance with the invention, but 6 having a sand-distributer separate from the rammer, and being also in construction and arrangement of other parts different from that shown in Fig. 1. The scale of Figs. 1, 7, and 8 is one-fifth of that of Figs. 2, 3, 4, 5, 6, and 9, so that if the scale of Figs. 1, 7, and 8 be ten centimeters to the meter, the other figures will be half of full size. Fig. 10 is drawn on an intermediate scale.

The same letters indicate like parts on all the figures.

Introduction of the sand.—The molding-sand is supplied, either by hand or mechanically, to the hopper B in a continuous manner during the operation, and passes from it into the tube forming the upper part of the rammer A. The flow is regulated by means of a valve or gate, L, which can be opened or closed more or less, as required, in any suitable way, as by the rod *l*, jointed at its upper end to an extension, *l'*, of the gate or valve, and placed within reach of the workman. The rod *l* is or may be pivoted to the frame. To prevent the sand from entering between the rammer A, or rather between the steel ring A', which is attached to the upper part of the rammer, and the stationary bronze ring A'', in which the latter slide without being able to turn, a conical piece, M of rubber or other suitable material, is fixed 2 one end to the top of the rammer and at the other to the cylindrical piece B' below the mouth of the hopper. This piece conforms 3 to the movement of the rammer, and, 4 it makes a tight joint at top and bottom, prevents the escape of sand around the rammer.

Reciprocation of the rammer.—The rammer A is raised by a cam, C, through the intermediary of the lever C', fulcrumed upon the 1

- q', and forked at one end to embrace the rammer and the ring D, fixed to the latter. The cam C is carried by the shaft q, which is rotated by gearing hereinafter described, and is adapted to raise the rammer to the required height. When the cam releases the lever C' the rammer is forced sharply downward by the joint action of its own weight and a spring, E, interposed between the ring A'' and the ring D. The sand delivered through the said distributor or hollow part of the rammer is thus compacted in the flask or molding-box G.*
- Construction of the lower part of the rammer.—* The lower part or head, a', of the rammer is made solid, (see Figs. 4 and 5,) and is attached by means of a screw, key, or other suitable device to the end of the tubular or hollow part, which is there provided with cross-plates that divide its interior into four conduits, a. These conduits terminate outside of the head of the rammer and distribute the sand around it upon the bottom of the mold. The rammer may be circular, oval, or of other form in cross-section; but the oval form is in general preferred.

- Table for the molding box or flask.—* The table or platform H is supported by a screw, I, and is guided by four rods, h h' h'', Figs. 1 and 7, fixed at their lower ends in the plates Y Y', and at their upper ends in the incomplete circle Z. In Fig. 1 this circle is shown partly cut away. The screw I is fastened to the table H and passes through the center of the wheel m, which is held between the plates Y Y', and has its bore screw-threaded to correspond with the thread of screw I. The table H is by the revolution of the wheel m raised or lowered, according to the direction in which it is turned,

Mechanism for connecting and operating the parts before mentioned.— Power is communicated in any ordinary or suitable way to the shaft n, which is supported in bearings by brackets attached to or forming part of the machine-frame, and from which the horizontal cam-shaft q and the vertical shaft t derive their movement. As shown, two pairs of band-pulleys, N N', are provided upon the shaft n, one of each pair being fixed and the other loose. A straight band runs upon the pulleys N and a crossed band upon the pulley N'. A spur-gear, P, and pinion p communicate the motion to the cam-shaft q. The pinion is made capable of sliding upon the shaft q, and is combined with a shifting-rod, b, and operating-lever b', so that it can be moved into and out of engagement with the gear P. Motion is communicated to the vertical shaft t by the bevel-gears o, and from the shaft t to the wheel n by the toothed wheel x, fixed upon said shaft. The band upon the pulleys N is used to drive the machine during the molding operations, the rammer A being reciprocated and the table I being caused to descend at an appropriate speed. The crossed belt upon pulleys N' is used to raise the table H into position for a new operation, the cam-shaft q stopping by disengagement of the pinion p.

Molding of various articles.— In case articles or patterns of various forms are to be molded, the clamp or molding box is placed upon a carriage, as k, Fig. 8, mounted upon rollers g, 70 so that it can be moved by a workman in all directions under the rammer.

Molding of circular articles or patterns.— If circular articles or patterns are to be molded, a chain-pulley, V, is supported upon the table H, so as to turn about the axis of the screw I, and the flask or molding-box rests upon a two-part auxiliary table or support, S S', which is connected with the chain-pulley V by pins s. The chain-pulley V, and with it the table S S', 80 is rotated by means of an endless chain or belt, T, Figs. 1 and 7, which runs upon the chain-pulley V. This pulley is connected with the shaft t by a spline or equivalent means, so that it is carried around with said shaft, but is capable of moving lengthwise thereon. An extension, W, of the table engages with the boss or center of the pulley and maintains it in the plane of the chain-pulley V. 85

Translatory movement of the rammer.— In order to vary the position of the rammer with respect to the table, the piece F at the top of the rammer is supported in ways or guides in the part Q of the machine-frame, and is combined with a screw-threaded shaft, R, by which it can be adjusted lengthwise of said part Q. The shaft R can be turned by a crank, e. This translatory movement is specially valuable in molding circular articles or patterns, but can be made available in operating with other kinds. 95

Removal of the pattern and return of apparatus into position for another mold.— When the flask or mold is filled with sand the rammer is stopped by disengaging the pinion p, but the table H is allowed to continue its descent. A 105 suitably-disposed stop enters a slot or opening in the table H, and, coming into contact with the outer part, S, of the table supporting the flask, prevents its further descent, while the pattern continues to descend with the part S' and the table H. When the pattern has been separated the movement of the table is stopped, and the pattern and flask, with the molded sand therein, are removed through the opening between the bars h' h'', Fig. 7. The table 110 H is raised rapidly by shifting the belt for the pulleys N' from the loose to the fixed pulley. When a new flask and mold have been placed in position and the table raised to the proper height, the belts are shifted, the pinion p is 115 moved into engagement with the gear P, and the delivery and compacting of the sand, as above described, are repeated.

Jointed or flexible rammer.— The upper or tubular part of the rammer, instead of being 125 rigid, can be provided with one or more articulations or joints on the ball-and-socket or analogous principle. The rammer can also be made flexible by forming it of two metal parts, a⁴ a⁵, connected by a flexible section, a⁶, as shown in 130 Fig. 9. This section can be formed of a spiral spring or two spiral springs wound in oppo-

site directions, and a covering inside or outside, or both, of rubber or similar materials, and leather, leather-cloth, and the like, separately or in combination with each other. The 5 flexible rammer enables small objects or patterns to be molded without shifting the flask or molding-box, the workman moving the head of the rammer as may be required. It is also advantageous in molding conical objects, as it 10 enables the proper inclination to be given to the rammer.

Apparatus with sand-distributer separate from rammer.—For molding patterns which require a large quantity of sand a difficulty or inconvenience is experienced in the use of a rammer made tubular to serve as the sand-distributer, since this, being of metal, and required to be strong to resist the impact of the rammer on the sand, is, when of the proper size, heavier 15 than is desirable. To overcome this difficulty a separate sand-distributer surrounding the rammer is employed. With this construction, as with the tubular rammer, the sand is compacted in the flask as it is delivered from the hopper. The rammer is or may be solid, and 20 can be formed of a bar adapted to withstand the longitudinal-compression strains to which it is subjected, and flexible in a lateral direction, or rigid, as may be preferred. The sand-distributer is preferably formed of rubber, 25 leather, or other flexible material, and it can be attached to the rammer, so as to rise and fall with it, or it can be attached to a stationary part of the machine. In either case it 30 accompanies the rammer or the head thereof in its lateral or translatory movement.

In Fig. 10 the sand-distributer A* is shown suspended from a plate, K, itself secured to the hanging bracket K', carried by the piece 40 or box F. The upper part is widened to form the hopper B. The rammer extends through the hopper and moves in guides in the piece or box F, and is reciprocated through the lever C' by means of the cams C on the shaft q, 45 which as shown is the main or power shaft. P' is a fly-wheel on this shaft q.

The sand can be introduced directly into the hopper by the workman, or by mechanical means; but it is preferred to introduce it 50 through the sieve L', to which a reciprocating movement is imparted in any suitable way, as by means of a rod or pitman, l', jointed at one end to the sieve and encircling at the other an eccentric-pin, l⁴, projecting from the face of a 55 disk carried by the shaft l³. This disk is connected with the shaft by clutch mechanism, so that it can be disengaged when it is desired to stop the sieve L'. The shaft l' can be driven from the shaft q.

60 In the apparatus shown in Fig. 10 the mechanism for operating the table carrying the flask or molding-box is also simplified.

The plate H is supported by the screw I, which passes through the chair or support I' 65 and engages with a nut formed by the center

of the chain-pulley V. Motion is communicated to the chain-pulley V from the cam-shaft q by means of the belt p³, running upon conepulleys s on the shafts q and m², the bevel-gears m' n', the vertical shaft t, the chain-pulley V' and the endless chain T.

It is obvious that the gearing is so calculated as to cause the table H and flask to descend the required distance for each revolution of the cam-shaft.

The dimensions, proportions, forms, and materials of the various parts can be modified without departing from the spirit of the invention. Accessory parts and the gearing or devices for transmitting motion can be varied 80 as desired.

Having now fully described the said invention and the manner of carrying the same into effect, what I claim is—

1. The combination, with the reciprocating 85 rammer, support for the flask or molding-box, and sand-distributer arranged to deliver the sand during the ramming operation, of means for regulating the supply of sand to said distributer, substantially as described.

2. The combination of a rammer and sand-distributer, the latter arranged to deliver the sand around the head of the rammer, substantially as described.

3. The combination of a rammer, sand-distributer, and table for the flask or molding-box with mechanism, as indicated, for reciprocating the rammer to pack the sand, and for causing the table to descend gradually as the sand rises in the flask or molding-box, substantially as described.

4. A flexible rammer for molding-machines, substantially as described.

5. The combination, with a reciprocating rammer, of a support for the molding box or flask, movable horizontally undersaid rammer, and means, as indicated, for automatically lowering said support, substantially as described.

6. The combination, with the rammer, of a movable piece or box supporting the same, as 110 described, whereby said rammer is capable of translatory movement.

7. The combination of a rammer and a flexible sand-distributer, substantially as described.

8. A flexible rammer and flexible sand-distributer, combined and operating substantially as described.

9. The combination, with the table and mechanism for raising and lowering it, of an auxiliary table carried by said first-named table, and means, as indicated, for revolving the said auxiliary table, substantially as described.

10. A sand-distributer combined with a rammer, substantially as described, so that it accompanies said rammer in its lateral movements.

11. An apparatus for molding sand comprising the following elements, combined and operating as described, namely: the rammer, cam-shaft, and intermediate devices for recip-

roating the rammer, the sand-distributer arranged to deliver the sand around the head of the rammer, and means for regulating the supply of sand to the distributer, and the table for the flask, and screw and connected devices for lowering and raising the table, substantially as set forth.

In testimony whereof I have signed my name to this specification before two subscribing witnesses.

J. D. DELILLE.
